United States Patent Office

Des. 220,320

Patented Mar. 30, 1971

220,320

AUTOMOBILE BODY

Richard L. Dirovizza, Redwood City, Calif., assignor to
Plastech Industries, Redwood City, Calif.

Filed Mar. 5, 1969, Ser. No. 16,051

Term of patent 14 years

Int. Cl. D12—08

U.S. Cl. D14—3

FIG. 1.

FIG. 2.

FIG. 3.

FIG. 4.

FIG. 5.

FIG. 1 is a perspective view of an automobile body showing my new design;

FIG. 2 is a side elevation as seen from the right in FIG. 1, the undisclosed left side is a mirror image of the right side;

FIG. 3 is a top plan view thereof;

FIG. 4 is a rear view thereof; and

FIG. 5 is a front view thereof.

The chassis and wheels, shown in broken lines, are included only for illustrative purposes.

I claim:

The ornamental design for an automobile body, as shown and described.
